UNITED STATES PATENT OFFICE.

MARK S. HUFF, OF SUTTON, WEST VIRGINIA, ASSIGNOR OF ONE-HALF TO
PEMBROKE B. BERRY, OF SAME PLACE.

ROTARY ENGINE.

SPECIFICATION forming part of Letters Patent No. 324,698, dated August 18, 1885.

Application filed June 8, 1885. (No model.)

To all whom it may concern:

Be it known that I, MARK S. HUFF, a citizen of the United States, residing at Sutton, in the county of Braxton and State of West Virginia, have invented a new and useful Improvement in Rotary Engines, of which the following is a specification, reference being had to the accompanying drawings.

My invention relates to an improvement in rotary engines; and it consists in the peculiar construction and combination of devices that will be more fully set forth hereinafter, and particularly pointed out in the claims.

In the accompanying drawings, Figure 1 is a side elevation of an engine embodying my invention partly in section. Fig. 2 is a transverse section taken on the line *x x* of Fig. 1.

A represents the bed of the engine, in the front end of which is journaled a circular piston, B, which is provided with trunnions C, and which has a grooved periphery, D.

At diametrically-opposite sides of the piston, buckets or abutments E are arranged transversely in the groove D, and an eccentric, F, is secured on one side of the piston.

G represents a semicircular case, which is bolted to or formed with the bed A, and which envelops the upper side of the piston. In a recess which is formed in this case is pivoted a gravity-valve, H, which rests normally in the groove D of the piston.

I represents a steam-chest, which is connected with the boiler, and is provided with an inlet-pipe, K, and an outlet-pipe, L, which extend through the case G and communicates with the groove of the piston just above the valve H. A slide-valve, M, reciprocates in the steam-chest, and is operated by a rod, N, and an eccentric-strap, O, which connect it with the eccentric F. A case, G, on the side opposite to the valve H, is provided with an exhaust port or pipe, P.

The operation of my invention is as follows: Steam is admitted from the steam-chest into the groove of the piston, and bears against

one of the buckets or abutments thereof and forces it around in the direction indicated by the arrow in Fig. 1. The valve H drops behind the abutment or bucket and prevents the escape of steam at that point. As the piston rotates, the eccentric works the valve in the steam-chest, and the eccentric and the buckets in the piston are so timed with relation to each other that the inlet-opening in the steam-chest is closed and the supply of steam cut off just before either of the buckets reaches the valve H. This relieves the pressure of steam on the valve H, and allows said valve to be raised by the bucket as it passes beyond it, and immediately thereafter the valve again sinks into the groove of the piston and a new supply of steam is admitted, which, by bearing between the valve H and the bucket, continues the impulse of the piston.

Having thus described my invention, I claim—

1. The combination of the rotating piston having the grooved periphery and the abutments or buckets, the case encircling the piston, and the valve H, pivoted in the case and bearing normally in the groove of the piston, substantially as described.

2. The combination of the bed-plate, the inclosing case G, having the valve H, the steam-chest, having the inlet-opening and the outlet-opening communicating with the case G, near the valve H, with the rotary piston, having the buckets and a grooved periphery, the valve H, bearing in said groove, a valve in the steam-chest for closing the supply of steam as the buckets reach the valve H, and the eccentric and rod for operating the valve, substantially as described.

In testimony that I claim the foregoing as my own I have hereto affixed my signature in presence of two witnesses.

MARK S. HUFF.
